UNITED STATES PATENT OFFICE

FRANK G. CARRINGTON, OF ANNISTON, ALABAMA, ASSIGNOR TO FERRIC ENGINEERING COMPANY, OF ANNISTON, ALABAMA, A CORPORATION OF DELAWARE

COOLING SYSTEM

Application filed March 9, 1927, Serial No. 173,903. Renewed August 9, 1930.

This invention relates to a cooling system, and more particularly to a cooling system in a centrifugal casting apparatus.

The cooling systems heretofore employed have taken the form in the past of either a jacket for a cooling medium surrounding the mold, or a member for sprinkling a cooling fluid upon the exterior surface of the mold. In either case, however, there have been certain undesirable results.

The temperature of any object is determined by its heat conductivity, the degree of heat or cold it is subjected to, and the time it is so subjected. In this connection we are chiefly concerned with the time factor. The cooling heretofore has been commenced at the same time along the entire length of the mold, and, inasmuch as the molten metal is poured longitudinally, there is a difference in the mold's temperature at different points along its length at the time metal is poured at such points. Assuming that the metal is poured at the bell end first and the trough gradually moved from that end toward the spigot, as is usually the case, that portion of the mold at the spigot end has been exposed to the cooling action for a greater length of time, at the moment the metal is poured there, than has the bell end. The metal therefore is poured into a cooler portion of the mold at the spigot end than at the bell. This difference in cooling results in a different texture of the pipe, for texture depends upon the cooling of the molten metal.

This differential cooling along the length of the mold not only results in defects in the casted objects, but causes uneven stresses in the mold itself. It has been found in practice that the mold fails at the spigot end after a relatively few casting operations.

Another defect in those systems heretofore employed has been that the casting is case-chilled because of the sudden cooling to which the metal is subjected. This is particularly true at the spigot end. Such a pipe is not commercially usable under ordinary circumstances, and in order to render the pipe fit for use, it is necessary to anneal it. An annealing process requires additional time and is a comparatively costly operation.

The problem therefore is to prevent overheating of the mold by cooling it uniformly along its length, and thus insuring its longevity, and on the other hand to cool the metal so gradually that annealing of the product will be obviated. To accomplish this is one of the objects of my invention.

Another object is to devise a method of sectionally cooling a rotary casting mold.

A further object is to provide a cooling system for sectionally cooling a rotary casting mold.

Yet another object of this invention is to provide a system whereby a mold may be cooled progressively along its length.

A still further object is to provide a cooling system whereby a section of a rotary casting mold is cooled and whereby this section advances along the length of the mold at a predetermined relationship to the pouring of metal within the mold.

To accomplish the foregoing objects, and other important results, as will more fully appear herein, my invention consists in a cooling member with means for regulating the operative length of said cooling member, and actuating means therefore adjusted to regulate the cooling at a predetermined relationship to the deposition of molten metal in the mold.

Reference is made to the accompanying drawings, in which is shown one form in which my invention may be embodied, but it is to be understood that many variations may be made in the structure set forth without exceeding the extent of my invention.

In the drawings:

Figure 1 is a sectional view along the longitudinal axis of a mold and cooling system and an elevational view of a ladling device and pouring trough;

Fig. 2 is a cross sectional view of the device shown in Fig. 1, along the line 2--2 of Fig. 1, looking in the direction of the arrows;

Fig. 3 is a more detailed view of the plungers and dispersing pipes shown in Fig. 1;

Fig. 4 is a view of the two dispersing pipes showing their relationship in cross section;

Fig. 5 is a view of the cooling system in

which the plungers precede the trough in their axial movement along the mold;

Fig. 6 is a view of the cooling system in which the cooling does not commence until after the metal has been deposited.

Referring in more detail to Fig. 1, there is shown a rotatable mold 1 supported upon trunnions 2, which in turn are mounted on roller boxes 3 fixed to the base 4 of the apparatus. The mold is shown with an enlarged end 5 for the formation of a bell, although such formation is not necessary for many pipes are cast without a bell formation. Lips 6 are provided to insure the retention of 15 poured metal in the mold when the metal is poured in that portion of the pipe. In the bell end of the pipe there is inserted and held, by suitable means not shown, a head core 7 with a shouldered portion 8. This core, together with the particular formation 5 of 20 the mold, provides a channel for the shaping of a pipe's bell. The head core may be withdrawn from the mold at the completion of a casting operation in order that the cast 25 pipe may be removed. A bearing member 9 serves to support the mold, and, by means of a guideway 11 therein and a corresponding groove on the circumference of the mold, prevents axial movement of the mold. The 30 bearing member 9 may be of the split type, or it may be provided with a split bushing. Gears 12 on the exterior of the mold mesh with other gears, not shown, which provide the driving force for the rotation of the mold.

35 Supported above the mold is a chamber 13 provided with apertures 14. The member 13 is supported by a standard 15 and also rests within the bearing member 9. While I have shown this chamber positioned above the 40 mold, it may be located at other points adjacent the mold with suitable provisions for directing a cooling fluid upon the exterior of the mold. Within the member 13 there are slidably positioned the plungers 16 and 17. 45 These plungers form watertight fits with the chamber and prevent the passage of a fluid beyond that portion of the member intermediate them.

While the plungers 16 and 17 may slide within the chamber, they are fixedly spaced with respect to each other by means of the pipe 18. This pipe is provided with apertures 19 for admitting a fluid into the chamber 13. The pipe 18 extends through the 50 plunger 17 and serves as a conduit from the source of supply of the cooling medium to the point of its dispersion. The plunger 17 is so mounted upon the pipe 18 that there is no opportunity for a fluid to pass through the 55 plunger except within the pipe.

It will therefore be seen that the chamber 13 can receive a cooling medium only from the apertures 19. The plungers 16 and 17 retain such a fluid within that portion of the 60 chamber intermediate them, and the only

method of escape of the cooling medium is through the apertures 14 of the chamber. The plungers are capable of sliding in the chamber but always in the same spaced relationship. As they so slide, that portion of the chamber in operation is varied and consequently that section of the mold being cooled.

70 There is also shown in Fig. 1 a ladle 21 which is mounted upon a truck 22. The truck is provided with wheels 23 and rolls on a track 24. Mounted on the truck, and extending beneath the ladle 21, is a pouring trough 25 from the spout 26 of which there is discharged a stream of molten metal 27. A bracket 28 supports the pipe 18 and provides that a movement of the truck, and consequently of the trough results in movement of the plungers 16 and 17. A flexible conduit 29 connected with a source of supply conveys a cooling medium to the pipe 18, 80 from whence it is dispersed by the apertures 19 in the pipe 18. A valve preferably a pressure regulating valve, is located on the conduit 29, but is not shown in the drawings. The amount of cooling medium dispersed on 90 the mold may be regulated by this valve.

95 In a casting operation the truck 22 is moved to the left until the spout 26 of the trough is at approximately 31. In this position the plunger 16 is adjacent the end of the chamber 13. Molten metal is discharged from the ladle 21 into the trough and flows to the spout 26 where it is poured into the mold. At the time the pouring is commenced, a valve, not shown, on the feed line for the 100 cooling medium, is opened. The cooling medium flows through the conduit 29, the pipe 18, and that portion of the chamber 13 between the plungers 16 and 17 is filled with the cooling medium, and discharges the same 105 upon the exterior of the mold. The spout is retained at 31 momentarily, for a greater amount of metal is required for the formation of the bell than is required in the barrel of the pipe. When the bell has been formed, the truck 22 moves to the right. As it does, the plungers 16 and 17 are moved accordingly. It will be observed that a section of the mold is cooled immediately succeeding the point at which molten metal is being discharged from the spout. Only that portion 110 of the chamber 13 between the plungers contains the cooling medium, and only that part of the mold included within the area between the plungers is cooled.

115 The degree of cooling may be regulated by the valve, above referred to, for the amount and pressure of the cooling medium may be varied.

120 In Figure, a cross sectional view, there is shown the lateral arrangement of the apparatus. The particular shape of the standard 15 may be varied. An eye 32 is formed at its upper end for supporting the chamber 13. While I have shown only one chamber,

it is of course to be understood that a plurality may be provided. The exact location of the chamber with respect to the mold may also be altered, provided the cooling medium is dispersed upon the mold.

In Figure 3, a more detailed view of the plunger and chamber, the apertures 19 in the pipe 18 are shown perpendicular to the apertures 14 in the chamber. It is not essential that the particular relationship between the two sets of apertures be such as shown in the drawings, but this is preferable inasmuch as it insures a more even flow of fluid from the apertures 14. The pipe 18 is shown, by the dotted lines 33, extending within the plunger 17. The pipe 18 might terminate at the plunger 17 provided there are means for conducting the fluid to the interior of that portion of the pipe 18 between the two plungers.

It will be seen from the foregoing that the cooling of the mold and the poured metal is gradual. The mold is not prematurely cooled and the metal is poured into a mold of normal temperature. The cooling does not commence until the metal has been poured in the mold and continues for only a comparatively short time. The duration of the cooling, however, is sufficient to prevent any overheating of the mold. The cooling period is of course dependent upon the speed at which the plungers 16 and 17 slide in the chamber 13 and also upon the length of the pipe 18 intermediate the two plungers. It is to be observed that the cooling is continuous for all that portion of the mold containing the most recently poured metal, but does not cool continuously all of the mold in which the metal is deposited.

While I have shown the plungers in such a relation to the trough that the cooling commences with the deposition of metal within the mold, under certain circumstances this arrangement may be varied so that the cooling precedes or follows the pouring of the metal.

In Fig. 5, for instance, there is shown a system in which the mold is cooled before the metal is deposited. The plunger 17 precedes the spout in its movement the length of the trough, so that when the metal is poured it is deposited on a portion that has been prematurely cooled. The extent of this premature cooling can of course be regulated by varying the distance the plunger 17 precedes the spout.

There is depicted in Fig. 6, an arrangement whereby the cooling is delayed for an interval after the metal is poured. The metal cools to a certain extent without the aid of artificial means, but the cooling is hastened when the exterior of the mold is sprayed. The lapse of time between the pouring of the metal and its cooling may be varied to meet the exigencies of any casting operation.

A cooling system such as is the subject of

my invention obviates, or at least minimizes, the necessity for an annealing process. This results in a considerable saving in the cost of manufacture and greatly reduces the time necessary to secure a completed product.

In the specification and claims I have used such phrases as "cooling a progressive section of the mold." These phrases refer to the cooling of successive partially overlapping sections, each section (though of uniform length) varying very slightly in its co-extension with respect to the immediately preceding and succeeding sections. This results in a substantially flow-like advance of the cooling along the mold. In contra-distinction to the present system, reference is made to applicant's copending application Serial No. 172,355, filed March 3, 1927, in which there is an incremental cooling of the mold; and to applicant's copending application Serial No. 177,652, filed March 23, 1927, in which there is no overlapping of the various sections, and which results in abrupt and distinct stages in the advance of the cooling along the mold.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. A centrifugal casting apparatus comprising a mold, a cooling member, and means for limiting the cooling to a section of the mold, the section progressing the length of the mold and including that portion of the mold where metal is being poured.

2. In an apparatus for centrifugal casting, a cooling system for a rotatable mold, comprising a fluid dispersing member and slidably mounted in the member plungers stationary with respect to each other.

3. In a cooling system for a rotary mold, a member adapted to disperse a cooling medium on the mold, plungers slidably mounted in the cooling member, and means for maintaining the plungers in spaced relation.

4. In a centrifugal casting apparatus cooling system, a fluid dispersing member, and slidably mounted therein plungers maintained in spaced relationship by an apertured member.

5. A cooling system for a centrifugal casting apparatus comprising a member adapted to disperse a cooling medium, slidable plungers fixedly spaced with respect to each other mounted in the member, means for actuating the plungers and supplying the member intermediate the plungers with a cooling medium, said means coating with a trough for pouring metal in the mold.

6. A centrifugal casting apparatus comprising a mold, a cooling member and means for limiting the cooling to a section of the mold, the section progressing the length of the mold.

⁵ In testimony whereof I affix my signature.

FRANK G. CARRINGTON.
